Primary Examiner — Cynthia Underwood(74) *Attorney, Agent, or Firm* — Taylor J. Ross(57) **CLAIM**

The ornamental design for an infant feeding bowl, as shown and described.

DESCRIPTION

FIG. 1 is a top, side and front perspective view of an infant feeding bowl showing my new design;

FIG. 2 is a top plan view thereof;

FIG. 3 is a bottom plan view thereof;

FIG. 4 is a front elevation view, the rear elevation being a mirror image thereof;

FIG. 5 right side elevation view thereof;

FIG. 6 is a left side elevation view thereof; and,

FIG. 7 is cross-sectional view taken along line 7-7 of FIG. 2.
